Attorney

UNITED STATES PATENT OFFICE

JOHN A. VILLOCHI, OF EASTON, PENNSYLVANIA

DISPENSING CONTAINER

Application filed March 6, 1931. Serial No. 520,669.

My invention relates to a dispensing container more particularly intended for dispensing small elongated articles, such as cigarettes or the like, although it is not limited to the dispensing of any specific article.

More specifically, the invention relates to a container or receptacle for cigarettes or the like which is arranged to slide on a stationary base, and has means whereby a cigarette will be fed from the receptacle into a groove in the base each time the receptacle is manually moved forward against the resistance of a suitable spring or the like concealed in the apparatus and returned by said spring to normal position.

My invention includes a magazine or casing having above its bottom a plate which slopes downwardly from the rear wall toward the front wall of the magazine and terminates short of the latter wall in a downwardly extending lip. The bottom of the receptacle also terminates short of the front wall of the receptacle and has at its forward edge an upwardly extending lip which bears against the front side of the downwardly extending lip of said plate. Thus an opening is formed at the forward end of the bottom of the receptacle through which articles in the receptacle may drop into the groove in the base when the casing moves forward. When the casing is returned by the spring to normal position the opening is closed by the upper surface of the base. The term "plate" is used in a broad sense since a solid block properly recessed would be an obvious equivalent.

My invention also includes a feeder having downwardly converging front and rear walls and a rearward extension from its upper rear angle. This feeder is located in a recess in the forward ends of the bottom and plate of the magazine with the rear end of its extension pivoted at the rear edge of the recess. When the magazine is in its forward position the upper surface of the feeder is below the surface of the plate. When the magazine is retracted the feeder is lifted as it slides over a projection in the bottom of the casing, thus rising above said plate and sepa-

rating a portion of the articles at the forward portion of the magazine from the main supply, and it exerting a straightening and compacting action on the cigarettes or other articles remaining in the magazine. As the magazine moves forward the front wall of the feeder and the upwardly extending lip at the forward end of the bottom act as plungers to force the separated articles into position for delivery.

For a better understanding of my invention reference should be had to the accompanying drawing illustrative of a preferred embodiment thereof, wherein:

Fig. 1 is a perspective view of the apparatus showing it with an article delivered into the groove of the base after actuation;

Fig. 2 is a longitudinal section of the device by a plane passing centrally through the same, the receptacle being in its rearmost position;

Fig. 3 is a view similar to Fig. 2 but showing the receptacle in its most advanced position;

Fig. 4 is a sectional view on the planes 75 represented by the line 4-4 of Fig. 2;

Fig. 5 is a perspective view of the actuating spring and bridge member, parts of the receptacle and base being broken away, and

Fig. 6 is a detail rear elevation of the plate 80 member or magazine floor and hinged feeding member of the receptacle.

Referring to said drawing, Fig. 1 shows a casing or receptacle 3 having a removable cover 4, mounted upon a stationary base 1, 85 the under side of which may be covered with felt or the like 2, as shown best in Figs. 2 and 3. Secured to the upper side of the stationary bottom 1 by means of bolts 6 and 7 and co-operating nuts 6a and 7a is a bridge member 90 9. This bridge member has a portion 9a depending from each end of its under side, which portions extend, respectively through a pair of longitudinally aligned slots 15 and 16 in the bottom of the receptacle. Thus the 95 part of the bridge member 9 which extends between its depending portions 9a overlies that part of the bottom of the receptacle which lies between the slots 15 and 16 so that the bridge member prevents detachment of 100

the receptacle from the base and its depending portions, by engagement with the ends of said slots, limit the forward and rearward movement of the receptacle on the base.

5 A spring 5, bent into suitable, preferably curved, form has its forward end secured to the base by the bolt 6 and its rear end bearing against the rear wall of the receptacle 3, said spring normally being under compression, whereby it tends to move the receptacle 10 3 rearwardly as far as the slots 15 and 16 permit.

Within the receptacle 3 and secured thereto in any suitable way, for example by means 15 of a bolt 10 and nut 11, is a plate or false bottom 8 which is inclined downwardly from the rear to the front of the receptacle, and terminates in a downwardly turned lip 8a at a point spaced from the forward end of 20 said receptacle. The bottom 14 of the receptacle also terminates short of the front wall of the receptacle and has at its forward edge an upwardly extending lip 14a which bears against the front side of the downwardly extending lip at the forward end of the plate or false bottom 8. The lip 14a and the front wall of the receptacle together form a passage of sufficient width to allow the article being dispensed to pass therethrough, as best shown in Figs. 2 and 3.

Referring now to Fig. 4, the forward ends of the bottom 14 and plate or false bottom 8 are cut out as shown at 22 to form a substantially rectangular notch in which is located the rear end of an article-feeding member 17 hinged on a rod 18 as shown. This article-feeding member in the form illustrated is substantially trapezoidal in cross section, as shown clearly in Figs. 2 and 3, 40 with an extension running from one vertex to the hinge rod 18. Since the rear end of the member 17 is loosely pivoted at the hinge joint, its forward end will be caused by gravity to drop below the plate or false bottom 45 8 if nothing prevents such descent thereof, as shown in Fig. 3, for instance, but when the spring 5 retracts the receptacle 3 to its rearmost position, said trapezoidal part of the member 17 will abut against the upper 50 end of the bolt 6, which constitutes an abutment that will raise the member 17, by acting as a stationary cam, into the position shown in Fig. 2.

The base 2 has a transverse groove in its 55 upper side adjacent its forward end to receive a cigarette or other article from the receptacle 3 each time the receptacle is moved forward to bring the opening between the forward end of the bottom 14 and the front wall of the receptacle above said groove.

For convenience in moving the receptacle 3 to its forward position with respect to the base 1, finger grips 12 and 13 are provided on the base 1 and receptacle 3 respectively, which when gripped by the fingers, as indi-

cated in Fig. 1, and drawn together, will cause the receptacle 3 to move forwardly with respect to the base 1 against the opposing force of the spring 5, and said spring 5 will cause the receptacle to return to its rearmost position as soon as the pressure of the fingers on the grips 12 and 13 ceases. 70

It will thus be seen that each time the receptacle 3 is moved forward with respect to the stationary base 1, the member 17 will descend to the position shown in Fig. 3 and that said member will again be returned to its raised position, as shown in Fig. 2, whenever the spring 5 returns the receptacle to its rearmost position. 75

These motions will serve to feed the articles 21 contained above the plate 8 in orderly fashion to the opening or slot in front of said member 17 and between it and the front wall of the receptacle 3, whereby jamming of the 80 said opening is prevented.

The groove 19 in the base 1 is made of sufficient depth to clear the article to be dispensed, so that the receptacle 3 will not catch on said article at the beginning of its return motion, thus leaving the article, here shown as a cigarette, upon the return of receptacle 3 to its rear position. The cigarettes or the like 21 stored in the magazine above its floor 8 will thus be fed one at a time in orderly fashion, without jamming, into the groove 19, so that in order to obtain an article it is necessary only to apply pressure of the fingers to the finger grips 12 and 13 to bring them together and thereupon to release them again. 95

Referring to Figs. 2 and 3, it will be observed that as long as more than one cigarette remains in the magazine, there will always be a reserve in the passage at its forward end, arranged one above the other, so that when one cigarette is deposited in the groove 19, another is ready to fall into the groove at the next operation. Sometimes, when the articles are hurriedly deposited in the magazine, they become slightly disarranged and lie in a more 110 or less criss-cross order, and sometimes the article itself is flat on one side or otherwise irregular in shape, so that gravity alone would not insure a feed at every operation of the device, but with my feeder there is a 115 packing action on each return movement of the receptacle, tending to straighten the articles remaining in the magazine above the feeder, and a positive thrust against the articles in the forward passage on each forward movement. If at any time a cigarette should fail to roll down from the main supply into the passage when the receptacle moves forward, there would still be one or more left in the passage after the lowermost 120 one has been deposited, and, before this reserve could be exhausted, those in the main supply would be sufficiently agitated and straightened to permit one or more to fall into the passage. Once in the passage there

125

can be no failure, for at every forward movement the feeder acts as a plunger to force the articles in front of it into exact vertical arrangement over the groove 19.

5. By turning down the forward end of plate 8, I increase the depth of the passage, thus providing space for separating one or more cigarettes from the main supply, and to these is added at least one more which rolls over 10 the feeder into the passage as the receptacle returns.

It is clear that the device may be modified in many ways, for instance, a spring of any other form may be substituted for the spring 15 5, and it is likewise clear that other means could be substituted for bridge 9 to accomplish the same result. Also, the magazine may be fixed and the base movable. In this case the only essential functions of the base 20 are its uses as a sliding closure for the passage, and as a support or actuator for the projection which lifts the feeder. The base may be in the form of a plate, curved to form groove 19. Accordingly, I do not limit myself 25 to the specific structures illustrated, except as hereinafter claimed.

I claim:

1. An article delivery apparatus, comprising a base having a pocket in its upper surface adjacent its forward end, a magazine 30 slideable lengthwise of said base, means urging said magazine rearwardly on said base, a plate inclined downwardly from the rear wall of said magazine, said plate having its 35 forward end turned downwardly rearwardly of the front wall of the magazine and forming with the latter wall an outlet adapted, when the magazine is moved forwardly, to align with the pocket in the base, said plate 40 having a recess in its forward end, a feeder hinged adjacent its rear end in said recess with its forward end substantially in vertical alignment with the downwardly turned portion of said plate and caused by gravity to 45 depend below the upper surface of said plate when the magazine is positioned with its outlet over the pocket of the base, and means on 50 said base engageable with said feeder during the rearward movement of said magazine 55 relatively to said base to lift the forward end of said feeder above the upper surface of said plate.

2. An article delivery apparatus, comprising a base having an article-receiving pocket 55 in its upper face adjacent its forward end, a magazine slideable longitudinally on said base, yieldable means urging said magazine rearwardly on said base, a plate inclined downwardly from the rear wall toward the front 60 wall of the magazine and terminating short of the latter wall and forming with the latter wall an outlet adapted to register with the pocket of the base when said magazine is moved forwardly on said base, said plate 65 having a portion of its forward end cut away

between its lateral edges, a feeder of substantially V-shape in cross section hinged at its rear edge adjacent the rear edge of said cut away portion with its forward end in substantially vertical alignment with and urged by gravity below the forward end of said plate, and means on said base engageable with said feeder when said magazine is moved rearwardly on said base to lift the forward end of said feeder above the forward end of said plate.

3. A delivery apparatus comprising a base, a casing mounted thereon having aligned slots in its bottom, and a bridge member having downwardly projecting ends extending 80 through said slots and secured to said base.

4. A delivery apparatus comprising a base, a casing slideable on said base and having aligned slots in its bottom, and a bridge member having downwardly projecting ends extending 85 through said slots and secured to said base; a feeder in said casing, and means securing said bridge member to said base, said means being operative, when said casing is moved on said base, to actuate said feeder.

In testimony whereof I have hereunto set my hand.

JOHN A. VILLOCHI.
